Thermal Cut-Out for Electrical Circuits.

1,278,467.

Specification of Letters Patent. Patented Sept. 10, 1918.

Application filed March 21, 1917. Serial No. 156,423.

To all whom it may concern:

Be it known that we, HENRY A. HOESCHEN and WILLIAM H. HOESCHEN, citizens of the United States, and residents of Omaha, in the county of Douglas and State of Nebraska, have invented certain new and useful Improvements in Thermal Cut-Outs for Electrical Circuits, of which the following is a specification.

- 10 Our invention relates to devices for automatically opening an electrical circuit when the current in the circuit exceeds a predetermined maximum and is maintained for a sufficient time to cause heating of a conductor forming a part of the circuit. It is the object of our invention to provide a simple and inexpensively constructed device of this kind, provided with means for causing an alarm when it operates to open the circuit, 20 and which may be readily restored to operative condition without replacement of any of its members. A further object of our invention is to provide in a device of this class means for automatically compensating 25 for temperature changes caused by means other than the flow of current in the circuit, so that the thermal expansion causing the cut-out operation will be substantially independent of atmospheric temperatures.
- 30 In the accompanying drawings, Figure 1 is a front view of a device embodying our invention, Fig. 2 is a side view of the same, Fig. 3 is a detail vertical section on the plane of the line 3—3 of Fig. 1, and Fig. 4 is a detail horizontal section on the plane 35 of the line 4—4 of Fig. 1.

In the illustrated embodiment of our invention we provide a cylindrical or tubular member 5 which is held in a fixed, preferably vertical, position by means of a supporting bracket connected therewith intermediate its ends. Said bracket comprises a base portion 6 which is attached to a suitable support, and an annular clamp-portion 7 which 45 encircles the member 5, said clamp-portion having its front side lugs 8 divided by a kerf, and said lugs being drawn toward each other by clamp-bolts 9 extending transversely through them, as shown. Near the upper end of the member 5 there is a clamp-ring 10, similar to the annular portion 7 of the supporting bracket, said ring having at the front side thereof lugs 11 which are drawn toward each other by a clamp-bolt 12

to close the ring upon the tubular member. 55 A ring or sleeve 13 of insulating material is placed around the member 5 within the ring 10, so that the latter is electrically separated from the former. A ring 14 is clamped on to the member 5 near the lower 60 end thereof. Another ring 15 is clamped thereon slightly below the ring 10, and a pair of rings 16 and 17 are clamped thereon below the bracket-ring 7, all 65 of said rings having insulating sleeves 13 between the same and the supporting tube 5, and being clamped similarly to the ring 10. The ring 14 has an integral laterally extending lug or arm 18 which is terminally forked and curved downwardly into a plane 70 beneath the end of the tube 5. A latch-bar 19 is pivoted on a pin 20 between the forked terminals of said arm 18, said bar 19 extending across beneath the end of the tube 75 and being movable in a vertical plane. In the lower end of the tube 5 there is a plug or socket 21 of insulating material, having therein a cylindrical recess in which is held a coil spring 22, the lower end of said spring 80 engaging the latch-bar 19 to yieldably press the same downwardly. The latch-bar is held in a substantially horizontal position by means of a rod or wire 23 of electrically conductive and thermally expansible material, the lower end of the wire extending 85 through an opening in the bar near the pivoted end thereof and having an integral enlarged portion or button 24 fitting in a recess therefor in the lower side of the bar. The upper end of the wire 23 has an integral 90 upset or enlarged threaded portion 25 which passes slidably through a vertical opening in a lug 26 extending laterally from the clamp-ring 10, and said threaded head-portion is held in adjusted relations to said lug 95 by means of nuts 27 and 28 screwed thereon above and below the lug, as shown. Extending laterally from the clamp-ring 15, and integral therewith, is a head 29 having a flat vertical outer face to which the upper end 100 of a flat spring 30 is secured by means of screws 31. Said spring 30 is formed or biased so as to tend to assume the curvilinear form indicated by dotted lines in Fig. 1. The lower end of said spring is normally 105 engaged by a hook or shoulder 32 near the end of the latch-bar 19 and the spring is thereby held in the rectilinear form shown

by full lines in the drawing. Near said lower end of the spring 30 there is secured on the inner side thereof a U-shaped contact-plate 33 of which the sides are kerfed to 5 form resilient fingers which embrace and frictionally engage a pin 34 carried by the latch-bar 19. On the head 29 and the side of the ring 10 there are provided binding-posts 35 and 36, or other suitable means for 10 connection with the terminals M of an electrical circuit, so that the same will be completed through the parts 30, 33, 34, 19, 23, 25, 26 and 10, when the spring 30 is in its normal or engaged relation to the latch-bar 15 19. It may be noted that, besides the principal electrical connection between the spring 30 and the latch-bar 19, afforded by the parts 33 and 34, the spring also directly engages and is in electrical connection with 20 the shoulder 32 of the bar. The parts 5, 23 and 30 are preferably made of metals having the same or substantially the same coefficient of thermal expansion, and the spring 30 is so proportioned as to have considerably 25 greater electrical conductivity than the wire or rod 23.

In consequence of the described construction, arrangement and proportioning of the parts, when the device is in use in an electrical circuit passing through the same as described, and the amount of current flowing in the circuit is great enough and is continued for a sufficient time to cause heating and a resultant predetermined expansion 30 of the member 23, the latch-bar 19 is lowered sufficiently to release the spring 30 from the hook or shoulder 32. Thereupon said spring rapidly assumes the curvilinear form to which it is biased, and disengages the resilient fingers of the contact-plate 33 from the pin 34, thus opening the circuit at this point. Ordinary or atmospheric changes of temperature of the mechanism will have no appreciable effect thereon, since the 35 length of the members 5, 23 and 30 is so nearly the same that there will be no material variations in their relative lengths due to such changes of temperature.

Simple and convenient means for indicating, at a distance therefrom, the operation of the cut-out mechanism, are provided as follows: On the clamp-rings 16 and 17 are integral laterally extending arms 37 and 38 which pass behind the rear edge of the 40 spring 30 and have terminal portions which extend forward laterally of said spring. To said terminal arm-portions are secured resilient contact-plates or springs 39 and 40, of which the first carries, near the end 45 thereof on the side adjacent to the spring 30, a button 41 of insulating material, which said spring 30 engages in assuming the curvilinear form thereof. The spring contact 39 is thereby pushed outward sufficiently to engage the inturned end-portion

of the plate 40 and form electrical connection therewith. The arms 37 and 38 carry binding-posts 42 for connection with wires 43 extending to and forming a circuit through a suitable battery or electrical 70 source 44 and a signal device such as a bell 45. It will be seen that upon operation of the cut-out device to open the main circuit, the signal-circuit will be closed to operate the bell or like device. 75

Under ordinary conditions, after the main circuit is opened and the flow of current through the wire 23 ceases, the wire will quickly cool to atmospheric temperature, simultaneously contracting to its normal 80 length and restoring the latch-bar to position for engaging the spring 30. Then, if the conditions which caused the overloading of the circuit have been remedied, the cut-out may be manually restored to its normal 85 circuit-closing position, by reengaging the spring 30 with the latch-bar, the spring being momentarily bowed intermediate its ends sufficiently to enable the lower end to pass in over the hook or shoulder 32. 90

In the event that the cut-out is to be used in a main circuit carrying normally a relatively large current, so that the wire 23 may be of such size as to have considerable rigidity without the conductivity thereof being so great as to prevent its heating by an overload of the circuit, the spring 22 need not be used, and the expansion of the wire may be employed directly to actuate the latch-bar to release position. Said spring 100 22 is, of course, used whenever the thickness of the member 23 is so small in proportion to its length that it is incapable of exerting a thrust upon the latch-bar.

Now, having described our invention, 105 what we claim and desire to secure by Letters Patent is:

1. An overload cut-out for electrical circuits, comprising an expansible tubular support, a plurality of clamp-rings disposed thereon and insulated therefrom, a circuit-breaking device biased to open-circuit position and carried by said clamp-rings, means mounted on one of the clamp-rings at one end of the support for retaining the circuit- 110 breaking device in closed-circuit position, and an expansible conductor connected with and controlling said retaining means, said conductor being connected in a circuit with said circuit-breaking device and extending 115 alongside the support from end to end thereof, one end of the conductor being secured to a clamp-ring at the end of the support opposite the retaining means for the circuit-breaker, and the conductor and support being equally expansible by like temperature-changes thereof. 120

2. In a device of the class described, a metal support mounted for free longitudinal expansion, a thermally expansible conductor 125

of like material and length extending longitudinally of said support, insulating connecting means between said conductor and support at one end thereof, a latch-bar pivotally connected with the support at the opposite end thereof and connected with the conductor to move in accordance with dif-

ferences of longitudinal expansion of the same and the support, and a circuit-breaking device connected in a circuit with the 10 expansible conductor and normally held by the latch-bar in closed-circuit position.
